[57] CLAIM

The ornamental design for a noise maker attachment for roller skates, as shown and described.

DESCRIPTION

FIG. 1 is a perspective view of a noise maker attachment for roller skates showing my new design, a fragmentary portion of a roller skate being shown in broken lines for illustration purposes only;

FIG. 2 is a left side perspective view thereof;

FIG. 3 is a left side elevational view thereof; and

FIG. 4 is a right side elevational view thereof.
